UNITED STATES PATENT OFFICE.

DAVID WEISZ, OF NEW YORK, N. Y.

COMBINATION GARMENT AND CARRIER BAG.

Application filed October 4, 1927. Serial No. 223,988.

The present invention is concerned with the provision of a combined garment and carrier bag of the same general character disclosed in my copending application Serial 5 No. 213,896, filed August 18, 1927. In accordance with the present invention however, the prior device is materially improved in that the carrier bag for the garment may be entirely concealed when the garment is 10 worn, and will not detract in any manner from the attractive appearance of the garment.

A further feature of the invention is the provision of a garment and carrier bag 15 combination in which the bag may conveniently serve as a hat or hood when the garment is worn, and as a container for the garment when the latter is being transported.

20 While the present invention finds its preferred embodiment in a raincoat, it should be understood that the range of bag and garment combinations which may be produced in accordance with this invention is practically limitless. The bag may be combined with various working garments such as aprons and overalls, with bathing garments, beach robes, trousers, etc.

Objects of the invention are to provide a 30 device of this character of neat, attractive appearance, which will be extremely simple and practical in construction, well suited to the requirements of economical manufacture and convenient packing or unpacking.

35 With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

40 Fig. 1 is a perspective view showing a raincoat embodying the present invention in use.

Fig. 2 is an inside plan view showing the raincoat opened up and the mouth of the pocket closed.

Fig. 3 is an enlarged vertical sectional detail on the line 3—3 of Fig. 2.

Fig. 4 is a fragmentary sectional perspective detail showing the bag turned right-side-out and ready to receive the garment.

Fig. 5 is a perspective view showing the position of the parts just before the folded garment is inserted in the bag.

Fig. 6 is a perspective view showing the bag closed with the garment therein.

Fig. 7 is a transverse sectional view through the bag and enclosed garment, showing the manner in which the bag may be secured by the button fasteners without turning the bag right-side-out.

As suggested above, the bag may be combined with any class of garment. I have elected to show it in combination with a raincoat. The drawings are not to be interpreted in a limiting sense, since they are 70 illustrative of only one embodiment of the invention.

I have used the reference numeral 10 to designate a raincoat of conventional external appearance provided with sleeves 11, 75 a belt 12 and a collar 13. The garment at its upper end may, if desired, be reinforced by a yoke piece 14 of any desired nature, this yoke piece being connected to the collar seam 15. Connected to the collar seam, preferably by the same line of stitching which secures the yoke piece 14, is a neck-protecting flap 16 to which is sewed the carrier bag 30. The end of this flap passes through the open mouth of the bag when the latter 85 is right-side-out as in Figs. 4, 5 and 6. This bag is of proper size and shape to receive the flap together with the raincoat when the latter is in folded condition, and the mouth of the bag is preferably closed 90 by a conventional type of closure device, such as the rows of hookless fasteners 17 and the sliding locking device 18 which cooperates therewith to draw the fasteners into interlocking relationship.

When the coat is worn the bag is turned inside-out as in Figs. 1, 2 and 3 and the flap 16 and the bag 30 which it carries may if

desired, lie within the coat, affording additional protective material across the wearer's back and between the shoulders. Preferably however, the flap 16 is turned outwardly 5 as indicated in Figs. 1 and 2, and the mouth of the bag is opened by manipulating the slide 18, so that the bag 30 may conveniently serve as a hood with the flap 16 embracing and protecting the nape of a wearer's neck.

10 The slide member 18 is preferably of the same character disclosed in my copending application above referred to; in other words, of a character which may be conveniently manipulated with the bag right-side-out or inside-out, due to the fact that its handle 18^a is pivotally mounted on an eye 18^b at one end of the slide and may be moved around the end of the slide from one side to the other whenever the slide is in any 20 position except its extreme fastener closing position.

When the garment is to be transported, the bag is preferably turned right-side-out as seen in Figs. 4 and 5, and the garment is 25 rolled up, or folded and inserted into the bag together with the protective flap 16, at which time the slide member 18 is operated and the bag mouth closed with the garment inside, as seen in Fig. 6.

30 If desired, instead of the form of fastener illustrated at 17 and 18, I may use ordinary buttons 20 carried by the inside of the bag adjacent the mouth, and buttonholed tabs 21 preferably anchored to the opposite 35 side of the bag adjacent the mouth and within the bag. In order that the tabs may be concealed when the bag is used as a hood as seen in Fig. 1, suitable slots 22 are provided in the flap 16, so that the tabs may be 40 passed through the slots and lie inside the flap 16. By providing a second row of buttons 20^a outside of the mouth and slotting for the reception of the tabs, the button 45 fastener may serve as a reversible fastener as will be later described.

If the buttons are to be used as closures for the bag, there is no need for turning the bag right-side-out. It is simply necessary to withdraw the tabs 21 from the position 50 of Fig. 2, fold the garment and insert it with the flap 16 into the bag mouth between the rows of slide fasteners which are thus rendered inoperative, and then button the tabs over as indicated in Fig. 7. When 55 using the buttons the flap and garment are folded directly into the bag from the position of Fig. 3, in which figure it will be recalled the bag is shown as inside-out. It 60 will also be noted that with the parts in the position of Fig. 4, if the tabs are not removed from the slots, the coat may be folded inside of the bag and the buttons as well as the slide fasteners used to doubly secure the bag mouth. Obviously the hook-

less fastener could not be used without turning the bag right-side-out, since the insertion of the coat into the bag while the latter was right-side-out, would result in disposing the material of the coat between the two cooperating rows of fastening elements. 65 70

It is not essential that both types of fasteners be used with a single bag, and they are illustrated here rather to indicate that either type might be used, and either type be arranged to serve as a reversible fastener. 75 Similarly, I have shown the use of handle straps 25 at both the inside and outside of the bag, so that a strap is provided whether the buttons or the hookless fastener elements are used to close the bag. 80

Obviously, various changes and alterations might be made in the general form and arrangement of the parts described without departing from the invention. Hence I do not wish to limit myself to the details set 85 forth, but shall consider myself at liberty to make such changes and alterations as fairly fall within the spirit and scope of the appended claims. 90

I claim:

1. In combination, a garment, a carrier bag, means attaching the same to the interior of the garment, said bag being adapted to be concealed by the garment when the latter is worn, fastening means adjacent the bag mouth so arranged that the folded garment may be inserted through the mouth of the bag and the bag closed when transporting the garment, the attaching means comprising a flap attaching the interior of the bag 95 to the garment adjacent the neck portion of the latter, whereby, with the flap outside, the bag may be opened and worn as an attached hood for the garment. 100

2. In combination, a garment, a carrier bag, means attaching the same to the interior of the garment, said bag being adapted to be concealed by the garment when the latter is worn, fastening means adjacent the bag mouth so arranged that the folded garment may be inserted through the mouth of the bag and the bag closed when transporting the garment, the attaching means comprising a flap attaching the interior of the bag to the garment adjacent the neck portion of the latter, whereby, with the flap outside, the bag may be opened and worn as an attached hood for the garment, the bag fastening means being operable to close the bag when the latter is turned either right-side out or inside-out. 110 115

3. In combination, a raincoat, a carrier bag, a flap secured to the interior of the bag and to the interior upper portion of the coat, whereby when the coat is worn, the bag may be concealed beneath the coat or worn as a hood with flap lying against the nape of the wearer's neck. 125

4. In combination, a raincoat, a carrier bag, a flap secured to the interior of the bag and to the interior upper portion of the coat, whereby when the coat is worn, the
5 bag may be concealed beneath the coat or worn as a hood with the flap lying against the nape of the wearer's neck, and reversible securing means at the bag mouth for closing

the bag right-side-out with the folded coat and flap concealed therein, or wrong-side-¹⁰ out and concealed under the coat when worn.

Signed at New York, in the county of New York and State of New York this 3rd day of October A. D. 1927.

DAVID WEISSZ.
